(57) **CLAIM**

What is claimed is the ornamental design for a shelf stop wall, as shown and described.

DESCRIPTION

FIG. 1 is a front top perspective view showing the shelf stop wall of Applicants' invention.

FIG. 2 is a rear bottom perspective view of the shelf stop wall of FIG. 1.

FIG. 3 is a front elevation of the shelf stop wall of FIG. 1.

FIG. 4 is a top plan view of the shelf stop wall of FIG. 1.

FIG. 5 is a bottom plan view of the shelf stop wall of FIG. 1.

FIG. 6 is a right side elevation of the shelf stop wall of FIG. 1, the left side elevation view being an identical mirror image thereto; and,

FIG. 7 is a rear elevation of the shelf stop wall of FIG. 1. The broken lines in the figures are used to represent subject matter that forms no part of the claimed design.

Where the figures show the article broken away, the break lines are understood to indicate unclaimed length, and any portion of the article between the break lines forms no part of the claimed design.
